STABILIZATION OF GLYCERIDIC OILS

Carl F. Brown, Jersey City, N. J., and Chester M. Gooding, Staten Island, N. Y., assignors to The Best Foods, Inc., New York, N. Y., a corporation of New Jersey

No Drawing. Application October 24, 1950,
Serial No. 191,915

13 Claims. (Cl. 99—163)

This invention relates to glyceridic oils and more particularly to glyceridic oils possessing marked resistance to deterioration.

An object of this invention is to retard the deterioration of glyceridic oils and more particularly hydrogenated and deodorized glyceridic oils, such as hydrogenated and deodorized soya bean oil.

Another object of this invention is to retard for relatively prolonged periods the development of rancidity of glyceridic oils.

A more particular object of this invention is to disperse uniformly throughout a body of glyceridic oil effective amounts of certain tricarboxylic acids which are capable of retarding the development of rancidity in such glyceridic oils.

Certain tricarboxylic acids are effective for retarding the development of rancidity of glyceridic oils. However, some of these tricarboxylic acids, such as citric acid, are only negligibly soluble in glyceridic oils and would be substantially ineffective for preventing flavor deterioration of such oils if added directly to the oil, particularly if a large body of oil were to be treated. Again, for small bodies of oil maintained at room temperature, the addition of such tricarboxylic acids, when added directly, might effect some degree of stabilization. If, however, such oils are required to be processed or used at elevated temperatures and under adverse conditions, the limited solubility of such tricarboxylic acids would not provide adequate concentrations to effect a useful degree of stabilization.

In accordance with this invention, tricarboxylic acids having six carbon atoms and no functional groups other than the hydroxyl group and the carboxyl group, are uniformly dispersed throughout a body of an edible glyceridic oil in concentrations sufficient to achieve maximum flavor stability under unfavorable conditions. For this purpose, a tricarboxylic acid having six carbon atoms is dissolved in any one or more of the following esters of polyhydric alcohols: Mono-fatty acid esters of glycerol, di-fatty acid esters of glycerol, mono-fatty acid esters of propylene glycol, or the condensation products of any of these esters with propylene oxide, the propylene moiety not to exceed four in such polymers. The resulting solution of the tricarboxylic acid in the ester is then added to the edible glyceridic oil, the tricarboxylic acid being uniformly distributed throughout the body of the oil by any suitable means, such as agitation. The fatty acids employed in the preparation of the fatty esters of the polyhydric alcohol may be any fatty acid, although preferably the fatty acid is a saturated or unsaturated fatty acid having from 12 to 18 carbon atoms, such as lauric, myristic, palmitic, oleic or stearic acids.

It is not understood how the practice of this invention results in a concentration of tricarboxylic acid in a triglyceridic oil markedly higher than that which can be achieved by the usual methods. However, while this invention is not restricted to any particular theory, it is believed that the addition of the compositions described herein to a triglyceridic oil results in establishing a favorable condition, wherein a very large surface of contact between the triglyceridic oil and the extremely finely dispersed tricarboxylic acid results from the rapid dilution of the compositions of this invention by the glyceridic oil at the time of admixture.

Examples of the tricarboxylic acid which may be em-

2

ployed in accordance with this invention are citric acid, aconitic acid, tricarballylic acid and iso-citric acid.

The tricarboxylic acid may be incorporated in the glyceridic oil by adding the solution of the tricarboxylic acid in the fatty acid ester of the polyhydric alcohol to the oil which is maintained in a liquid state. Any temperature at which the oil is completely liquid is satisfactory for this purpose. The tricarboxylic acid is uniformly distributed throughout the body of the oil by any convenient means of agitation, such as stirring. The means of agitation should be sufficiently rapid and thorough to insure the uniform distribution of the tricarboxylic acid throughout the body of the oil. A preferred method employs the use of a proportioning pump arranged to continuously inject the desired quantity of tricarboxylic acid into a stream of the oil to be treated as it is discharged from a deodorizer and while the oil being treated is still under vacuum.

A more comprehensive understanding of this invention is obtained by reference to the following examples:

Example 1

An eight per cent solution of anhydrous citric acid is prepared by dissolving eight parts of citric acid in a mixture of mono- and di-fatty acid esters of glycerol maintained at a temperature of 120-135° C. The mixture of mono- and di-fatty acid esters of glycerol contains more than 95% of the mono-fatty acid esters of glycerol and the remainder di-fatty acid esters of glycerol and the fatty acid esters consist principally of the monostearic acid and monopalmitic acid esters of glycerol.

0.25 part of the solution of the citric acid in the fatty acid esters of glycerol is added to 100 parts of hydrogenated and deodorized soya bean oil maintained at a temperature of about 60° C. The citric acid may be uniformly distributed throughout the body of the oil by subjecting it to mechanical stirring. Preferably, the solution of citric acid in the esters is injected into the oil stream continuously by employing the proportioning pump heretofore described.

Example 2

Five parts of citric acid monohydrate U. S. P. are dissolved in 100 parts of a mixture of about equal parts of mon- and di-fatty acid esters of glycerol which have been washed to free the mixture of glycerol. The fatty acids of the glycerol esters were obtained from corn salad oil.

This solution of citric acid in the mono- and di-fatty glycerides of corn salad oil fatty acids is used to treat corn salad oil at the time of completion of deodorization by means of the proportioning pump heretofore described. The proportioning pump is adjusted so that the citric acid content of the resulting oil is about 0.005%.

Example 3

Pure propylene glycol monostearate is prepared by the catalyzed condensation of propylene oxide with stearic acid. Seventy-five parts of propylene glycol monostearate are agitated with fifteen parts of powdered anhydrous citric acid for 45 minutes at a temperature of 60-65° C., after which the mixture is filtered. The perfectly clear and light colored product contains 1.3% of citric acid.

0.3 part of the solution of citric acid in propylene glycol stearate is added to a mixture of 60 parts of cottonseed and 40 parts of soya bean oils hydrogenated for making margarine. It may be incorporated in the oil by addition, with subsequent agitation, or by injection in a stream of the oil at a temperature of about 60° C. in the manner heretofore described.

Example 4

Five parts of aconitic acid are dissolved at 80° C. in 100 parts of the propylene oxide condensation product with the mono-fatty acid esters of glycerol employed in Example 1. The condensation product is produced by the reaction of one molecular proportion of the mono-fatty esters of glycerol with four molecular proportions of propylene oxide.

0.2 part of the solution of the aconitic acid in the fatty acid ester is added to 100 parts of a hydrogenated and deodorized soya salad oil and uniformly dispersed through-

3

out the body of the oil by either of the methods heretofore described.

Example 5

A seven per cent solution of tricarballylic acid in the oleic acid ester of tetrapropylene glycol is prepared by heating the two components together with stirring at a temperature of 90° C.

One part of the solution of tricarballylic acid in tetrapropylene glycol oleate is added to 100 parts of hydrogenated soya shortening oil at a temperature of above 60° C. prior to plasticizing. The tricarballylic acid is distributed uniformly throughout the oil by either of the practices heretofore described.

Example 6

Example 1 is repeated except that aconitic acid is employed instead of citric acid.

Example 7

Example 1 is repeated except that tricarballylic acid is employed instead of citric acid.

It is desirable that the amount of tricarboxylic acid dissolved in the fatty acid esters of the polyhydric alcohol be at a level of at least 0.5 part, and preferably at least one part of tricarboxylic acid to 100 parts of ester. It is also desirable that the amount of tricarboxylic acid incorporated in the edible glyceridic oil be within the range of 0.002 to 0.1%, and preferably within the range of 0.01 to 0.05% of the glyceridic oil.

By the term "glyceridic oil" is meant any glyceridic fat in liquid or solid form which may or may not be specifically processed to attain desirable properties, such as plasticity or melting point.

The terms and expressions which we have employed are used as terms of description and not of limitation, and we have no intention in the use of such terms and expressions of excluding any equivalents of the features described or portions thereof, but recognize that various modifications are possible within the scope of the invention claimed.

What is claimed is:

1. A method of retarding the development of rancidity of an edible glyceridic oil, said method comprising adding to said glyceridic oil an aliphatic tricarboxylic acid dissolved in an ester of a polyhydric alcohol and substantially uniformly distributing said aliphatic tricarboxylic acid through the body of said oil, said tricarboxylic acid having six carbon atoms and having no functional groups other than the hydroxyl group and the carboxyl group, and said ester being selected from the class consisting of mono-fatty acid esters of glycerol, di-fatty acid esters of glycerol, mono-fatty acid esters of propylene glycol and the condensation products of any of said fatty acid esters with not more than four molecular equivalents of propylene oxide.

2. A method of retarding the development of rancidity of an edible glyceridic oil, said method comprising adding to said glyceridic oil citric acid dissolved in a fatty acid ester of a polyhydric alcohol and substantially uniformly distributing said citric acid throughout the body of said oil, said fatty acid ester being selected from the class consisting of: mono-fatty acid esters of glycerol, di-fatty acid esters of glycerol, mono-fatty acid esters of propylene glycol and the condensation products of any of said fatty acid esters with not more than four molecular equivalents of propylene oxide.

3. A method of retarding the development of rancidity of an edible glyceridic oil, said method comprising adding to said glyceridic oil aconitic acid dissolved in a fatty acid ester of a polyhydric alcohol and substantially uni-

4

formly distributing said aconitic acid throughout the body of said oil, said fatty acid ester being selected from the class consisting of: mono-fatty acid esters of glycerol, di-fatty acid esters of glycerol, mono-fatty acid esters of propylene glycol and the condensation products of any of said fatty acid esters with not more than four molecular equivalents of propylene oxide.

4. A method of retarding the development of rancidity of an edible glyceridic oil, said method comprising adding to said glyceridic oil tricarballylic acid dissolved in a fatty acid ester of a polyhydric alcohol and substantially uniformly distributing said tricarballylic acid throughout the body of said oil, said fatty acid ester being selected from the class consisting of: mono-fatty acid esters of glycerol, di-fatty acid esters of glycerol, mono-fatty acid esters of propylene glycol and the condensation products of any of said fatty acid esters with not more than four molecular equivalents of propylene oxide.

5. A method of retarding the development of rancidity of an edible glyceridic oil, said method comprising adding to said glyceridic oil citric acid dissolved in a mono-fatty acid ester of glycerol and substantially uniformly distributing the citric acid throughout the body of said oil.

6. A method of retarding the development of rancidity of an edible glyceridic oil, said method comprising adding to said glyceridic oil citric acid dissolved in a di-fatty acid ester of glycerol and substantially uniformly distributing the citric acid throughout the body of said oil.

7. A method of retarding the development of rancidity of an edible glyceridic oil, said method comprising adding to said glyceridic oil citric acid dissolved in a mono-fatty acid ester of propylene glycol and substantially uniformly distributing the citric acid throughout the body of said oil.

8. A method of retarding the development of rancidity of an edible glyceridic oil, said method comprising adding to said glyceridic oil aconitic acid dissolved in a mono-fatty acid ester of glycerol and substantially uniformly distributing the aconitic acid throughout the body of said oil.

9. A method of retarding the development of rancidity of an edible glyceridic oil, said method comprising adding to said glyceridic oil tricarballylic acid dissolved in a mono-fatty acid ester of glycerol and substantially uniformly distributing the tricarballylic acid throughout the body of said oil.

10. A method as defined in claim 1 in which the edible glyceridic oil comprises hydrogenated deodorized soya bean oil.

11. A method as defined in claim 2 in which the edible glyceridic oil comprises hydrogenated deodorized soya bean oil.

12. A method as defined in claim 3 in which the edible glyceridic oil comprises hydrogenated deodorized soya bean oil.

13. A method as defined in claim 4 in which the edible glyceridic oil comprises hydrogenated deodorized soya bean oil.
